IRONING BOARD

Theodore S. Swarts, Burlington, Wash.

Application December 7, 1931. Serial No. 579,504

1 Claim. (Cl. 68—10)

My invention relates to improvements in ironing boards designed for being built in and has for an object to provide an ironing board which may be conveniently set at different elevations.

5 Another object of my improvement is to provide for limited oscillation of the board on a vertical axis and means to retain the board in desired positions in oscillation.

Other objects of my improvement will appear as 10 the description proceeds.

I attain these and other objects of my improvement with the mechanism illustrated in the accompanying two sheets of drawings, forming a part of this specification, in which Figure 1 is a 15 front elevation of my ironing board when fully closed, Fig. 2 is a rear elevation of Fig. 1, Fig. 3 is the same as Fig. 1 with the upper door standing open, Fig. 4 is a side elevation of the board when fully open in an operative position in elevation, 20 shown in section on a medial vertical plane, and with the board perpendicularly forward, Fig. 5 is a plan view of the board in operative open position with the board in an oblique position in oscillation, and Fig. 6 is a plan view of Fig. 4 in section 25 on the line 6—6 thereof.

Similar characters refer to similar parts throughout: Certain parts are broken away to show others hidden thereby.

With more particular reference to the designated parts: A frame more especially designed 30 for building in a wall has top and bottom ends 7, 7 and sides 8, 8 with said sides tied together by back cross pieces 9, 9. This will be referred to as the wall frame.

35 The board frame consists of top and bottom ends 10, 10, sides 11, 11 and back board 12. The board frame is mounted on a vertical axis for oscillation, preferably, using hinges 13, 13 for the same which connect the front edges of one of wall 40 frame sides 8 with one of board frame sides 11 thus mounting the board frame within the wall frame for oscillation from a position fully within the wall frame to a position partly outside of the same and oblique therewith.

45 The front of the upper part of the board frame is closable by door 14 hinged to one of the side boards 11 at 15, 15, and retained in a closed position by catch 16. The lower part of the front of 50 the board frame is closed by brace board 17, retained by hinges 18 and a18.

Two racks 19, 19 are fastened vertically to the inner sides of board frame sides 11, 11 at the front edges thereof with teeth 20 of the racks on the inner edge thereof spaced from back board 12. The

bottom ends a19 of the racks are devoid of teeth and chamfered on their inner edges.

The ironing board proper 22 has a crosspiece 23 fastened on its inner end with the ends thereof protruding beyond the edges of the board to 60 serve as teeth for engaging with the teeth 20 of racks 19. Slide board 24 is mounted in front of back board 12 in the space between the rack teeth 20 and said back board for reciprocation and across the lower rear part of the same is 65 fastened batten 25 which, together with the thickness of the slide board, nearly fills the space between said rack teeth and the back board except at the lower chamfered end a19 of the rack. On the top end of slide board 24 is fastened hook 70 26 protruding forward over the inner end of ironing board 22 to stop the upward movement of the inner end of the ironing board relative to the slide board. Across the lower part of slide board 24 on its front is fastened batten 21 between racks 75 19. Brace board 17 is hinged at its lower end at 18 to the front edge of batten 21 and at its upper end at a18 to the bottom side of ironing board 22.

In Fig. 3 the front elevation of the board assembly is shown with the ironing board 22 disclosed by opened door 14 in solid lines in its closed or shut-up position. In Fig. 4 said closed position of the board is shown in dotted lines at 22". When the board is in its closed position slide board 24 is at 24", in Fig. 4, and a tenon a24 80 85 on the lower end thereof is at a24" engaged in an opening b24 in the lower end 10 of the board frame.

The engagement of tenon a24 in mortice opening b24 retains the lower end of the movable part 90 of the board assembly in place when the board is folded up and closed. When in this closed position batten 25 is at 25" and brace door 17 is at 17" in Fig. 4.

When said board is in its closed position, referred to, it is opened and set in operative position by first opening upper door 14 after withdrawing catch 16 thereon, grasping the upper end of board 22 by hand, lifting upward and drawing outward thereon to set the board in its 95 position shown in solid lines in Fig. 4, when bar 23 engages a tooth 20 in each of racks 19, is retained in said engagement by the weight of the forward end of the board and batten 25 bears 100 against back board 12.

As illustrated in Fig. 4 board 22 may be set in any one of nine operative positions in elevation by engaging bar 23 in any one of the nine teeth 20 in racks 19. To move the board from one to another of these operative positions it is 110

grasped by hand, moved backward to disengage bar 23 from the teeth 20, when hook 26 prevents slide board 24 from moving below the board 22 and the board is moved upward or downward as desired, say upward to its dotted-line position at 22', when door brace 17 is at 17', the slide board is at 24', the back batton is at 25' and the front batton is at 21', while the cross bar is at 23'.

In connection with the closed position of the board at 22" in Fig. 4 it may be added that cross bar 23 thereon is at 23" having required the tapering chamfered ends a19 of the racks 19 to provide room for it to pass from its operative positions to the rear of the rack to its forward position at the said 23".

When in said closed position, as stated, upper door 14 may be retained closed by catch 16 thereon and brace board or door 17 is retained in place by hinges 18 and a18 and tenon a24 in mortice b24.

There is a movement of board frame 10, 11 and the board assembly therein on hinges 13, 13 yet to be explained. Latch a11 on one of frame sides 11 engages in a catch on wall frame side 8 to retain the board frame in closed position. When this latch is withdrawn the board frame could swing outward on hinges 13 except for bolts 27 and 28 mounted for reciprocation on the rear surface of back board 12. Bolt 27 is mounted for reciprocation in guide clips a27, a27 fastened on the back board; while bolt 28 is mounted for reciprocation in guide clips a28, a28 fastened on the back board to dispose the bolts parallel but offset from each other as shown in Fig. 2. The adjacent ends of the bolts terminate near the longitudinal center of the back board and are pivoted to the ends of lever 29 which is fastened to short shaft 35 at the middle of the lever. Shaft 35 is mounted for oscillation in a hole 40 through back board 12 and has bar 34 fastened on the front end thereof as shown in Fig. 3. A series of holes are provided in each wall frame end 7 as shown in the top plan view in Fig. 5 in the top frame end 7. These holes are in a row 45 arcuate on the axis of hinges 13, and the top holes 30, 31, 32 and 33 are disposed to be engaged by the upper end of bolt 27, while the bottom holes, only one of which is shown at 32 in bottom frame end 7 in Fig. 2, are disposed in an arc on said hinge axis each hole to pair with one of said top holes and any particular hole to be engaged by bolt 28 at the same time that bolt 27 engages the hole pairing therewith in said top frame end 7 as the board assembly oscillates on hinges 13.

When board 22 is in operative position, as at

22 or 22' in Fig. 4, bar 34 is accessible and may be turned by hand to withdraw bolts 27 and 28 from holes 32, in which they are shown as being engaged, then the board may be swung to any desired position on hinges 13, as to the oblique position shown in solid lines in Fig. 5 when the bolts are engaged in holes 32.

This provision for oscillating the board assembly on a vertical axis is useful when it has been found most convenient to place the board in the wall adjacent a corner of the room. In such cases, of course, it may be desirable to swing the board from its perpendicular position, as in Fig. 6, to an oblique position toward the right, rather than toward the left as shown in Fig. 5. In this case the hinges 13 would be fastened on the opposite side of the frames, bolts 27 and 28 would be mounted on the opposite side of the back board and holes 30—33 would be placed in rows arcuate with the other disposition of hinges 13 stated.

This ironing board assembly is well suited to be built into the wall or fastened to the surface of the same as preferred.

I prefer to make it principally of wood, the surfaces of all of which, except the ironing board proper are enameled or otherwise painted.

Having thus disclosed my invention, what I claim as new therein and desire to secure by Letters Patent is,—

In mechanism of the kind described, an ironing-board frame consisting of top and bottom ends, side pieces and backboard, said bottom end having an opening therein, a rack fastened on the inner wall of each side piece of the frame with the teeth thereof facing said backboard and spaced therefrom, a slide board mounted for reciprocation between said racks and the backboard, a tenon on the bottom end of the slide board engageable in said opening in the bottom end of the frame, a hook on the top end of the slide board extended forward, an ironing board, a crossbar fastened on the inner end of the ironing board having ends extended beyond the edges of the ironing board for engagement with said racks, said ironing board being mounted with its inner end in said frame with its crossbar beneath said slideboard hook, and engaged in said racks, a brace-board door having one end hinged to said slide board and the other end thereof hinged to said ironing board adapted to close the front of the lower part of the frame when said ironing board is disposed entirely within the same, and a door hinged to said frame to close the upper part of the front thereof.
